PRESSURE HOLDING AND DISPENSING CONTAINER

Richard H. Lindsey, Detroit, Mich., assignor to
Bundy Tubing Company, Detroit, Mich., a corporation of Michigan

Application December 9, 1946, Serial No. 714,963

2 Claims. (Cl. 299—95)

1

This invention relates to the art of storing a substance in a pressure holding container and dispensing the substance from the container by means of the pressure in the container.

One example is that of charging a vessel or container with a volatile liquid together with an insecticide. In a situation of this kind, the volatile liquid is charged into the container in liquid form for which purpose it may be reduced to a low temperature, and then the vessel is closed or sealed. In due course, the vessel and the contents reach ordinary room temperatures, at which temperatures the volatile liquid creates a pressure in the vessel, and when a small port is opened, there is a discharge of some liquid and vapor with discharge carrying some of the insecticide. Thus, the insecticide may be sprayed wherever desired. The pressure is maintained in the vessel in a substantially uniform manner from the time of the initial charge until the vessel is substantially empty of the volatile liquid.

The present invention is concerned with the vessel or container for substances or combinations of substances of the character above recited. It has been the practice to provide relatively expensive containers for this purpose which were designed with the intent that after the charge in the container is dispensed, the container is to be returned to the manufacturer or other plant for refilling.

The general object of the present invention is to provide a simple vessel with a sealing and spray device for materials of the type mentioned and which can be so cheaply manufactured that it is economically feasible to throw the container away after the contents have been discharged. Of course, it is within the invention to refill the container if such is desired, but even in this case the initial manufacturing cost and initial investment of the user is reduced.

As an example of the materials which may be used with the container, reference might be made to the use of the substance, commonly known as Freon, as the volatile charge which provides the pressure and serves as the carrier for the insecticide which can be the so-called DDT which is believed to have been developed during the recent war. Of course, the invention is not limited to any particular materials nor, for that matter, is it limited to the spraying of an insecticide as the container may be used for spraying any desired substance. Also, it might be said that when reference is made to "insecticide" that this term is used in its broadest sense.

A vessel constructed in accordance with the invention is shown in the accompanying drawings and in these drawings:

Fig. 1 is a side elevational view of a vessel embodying the structure of the invention with some parts cut away and some parts in section.

2

Fig. 2 is an enlarged cross sectional view taken substantially on line 2—2 of Fig. 1 showing the valving and spray devices.

Fig. 3 is a top plan view of the vessel.

Fig. 4 is a perspective view illustrating the top of the vessel and demonstrating its manner of use.

As shown in Fig. 1, the container is of cylindrical form, which is thought to be a convenient shape for the container, having a cylindrical wall 1 with a bottom wall 2 at one end of the cylindrical form and a top wall 3. This structure necessarily has the strength required to hold the internal pressure which is developed by the volatile substance and the top wall is preferably depressed as shown to thereby provide a recess 4 for accommodating the valve part and spray part.

There is a tube 6 mounted in the top wall of the container and for this purpose the top wall may be provided with an opening defined by a flange 7 in which the tube 6 is secured as, for example, by being soldered, thus to provide a liquid tight joint. The lower end of the tube is open, as illustrated, and adjacent its upper end, but just inside the top, the tube is provided with a small lateral opening 8. It will be appreciated, of course, that when terms such as "top" or "upper", or "bottom" are used, that these are relative terms. This is the position the parts are shown in the drawings and when in use, the container will usually be somewhere near an upright position; although this may not be necessary.

The top wall 3 is provided with a recess 10 for the reception of sealing material preferably in the form of a body of rubber, either natural or synthetic or of material similar to rubber. This material, which may be termed a packing, is shown at 11 and it has a passage therethrough and the tube 6 passes through the packing. The upper end of the tube is screw threaded as at 12 for the reception of a cap 15. This cap has an internal chamber as illustrated, and provided with internal threads for engagement with the tube and the cap is arranged to abut against the packing 11. The top of the cap is closed and is designed to freely receive a valve member preferably in the form of a ball 16 arranged to seat in the upper end of the tube which may have an internally bevelled seat 17 for receiving the ball. Mounted in the cap, at a position above the upper end of the tube 6, is a spray tube 20 having a relatively small passage 21 therethrough. The spray tube 20 has, preferably, a gas tight connection with the cap. If the cap 15 is a machined metal part, the spray tube 20 may be soldered thereto; if the cap be a die casting the tube may be cast in position; if the cap is of molded plastic the tube 20 may be molded to the cap.

The spray tube 20, as shown in Figs. 2 and 3, extends laterally from the center position of the cap and is confined in the recess 4. Preferably, both the cap 15 and the spray tube are disposed below the upper edge of the cylindrical wall of the container so that the parts are out of the way and protected in normal shipment and handling operations. As a safety factor, a locking device, such as an abutment or small plate 24, may be secured to the top plate 3 and positioned to be engaged by the tube 20 to prevent accidental turning of the cap on its screw threads.

As mentioned above, the vessel is charged with the volatile substance and the insecticide or other selected materials, while the volatile substance is in liquid form for which purpose the substance may be at a low temperature. The stop plate 24 may be attached to the container at the time and by the operation of sealing the top plate 3 after the vessel has been charged. Preferably, the arrangement of the cap and the packing is such that when the cap is screwed down to tightly engage the ball 16 with the seat 17, the packing has been compressed to some extent. When the cap is screwed down tightly against the ball, the packing material has been compressed by about two full revolutions on the threads 12. Due to the fact that the spray tube 20 has a small interior diameter, an opening at the valve seat 11 sufficient for the full capacity of the spray tube may be obtained by only a partial revolution of the cap 15. In this manner, even though the ball valve is fully open, to the capacity of the spray tube 20, the packing material remains compressed thus maintaining, at all times, a tight seal against the tube 6 to prevent leakage of the substance through the screw threads and packing.

When the vessel is initially charged the parts are intended to be in the position as substantially shown in Figs. 2 and 3 with the ball valve 16 seated tightly on the seat 17. This provides an effective seal for holding the contents in the vessel under the pressure developed. The packing 11 has been compressed as above pointed out and the tube 20 is so positioned as to engage the stop plate 24 to prevent the unscrewing action of the cap 15. When the device is to be used, the operator or user bends the spray tube 20 upwardly as indicated by the full-line position of the tube as indicated in Fig. 4, so that the spray of the substance will pass over the top of the container. Now, by turning the nut 15 to effect an unscrewing action, say for example, a partial turn as illustrated by the dotted lines in Fig. 4, the pressure on the ball 16 is relieved and thus the valve is opened. However, the packing 11 remains compressed to prevent leakage along the screw threads. Upon the opening of the valve, the pressure in the vessel causes a forceful discharge as indicated in Fig. 4. Some of the liquid may discharge up through the tube 6 from the bottom thereof while some vapors may enter the aperture 8 to effect an aspirating action. Thus, the discharged liquid or mixture of liquid and gas carries with it some of the insecticide for the spraying of spaces or objects.

I claim:

1. A container for holding and spraying a sub-

stance such as a volatile liquid carrier and an insecticide, a tube extending through a wall of the container and having a fluid tight seal with said wall, the end of the tube outside of the container projecting from the wall and having screw threads on its projecting end, a closed cap screw threaded on the tube and having a top portion overlying the open end of the tube, valve means within the cap engageable by the top of the cap to be urged against the open end of the tube to close the same as the cap is turned on its threads, restricted passage means in the cap for the discharge therethrough of substance from the container when the cap is turned on its threads to release the valve means, and a packing member comprising, a body of resilient packing material positioned around the tube and between the cap and the said wall of the container and normally compressed between the cap and the wall of the container to provide a fluid tight seal between the cap and the tube, said packing member having an axial extent such that when the cap is retracted from the wall of the container by the turning of the same on its threads, the packing member remains compressed to, at all times, maintain a fluid tight seal between the cap and the tube.

2. A container, for holding and spraying substance such as a volatile liquid carrier and an insecticide, a tube extending through and sealed to a wall of the container, valve means associated with the tube including an element rotatably mounted on the projecting end of the tube and turnable in one direction to close the valve means and turnable in the opposite direction to open the valve means, a spray tube mounted on said element and arranged to communicate with the first mentioned tube when the valve is opened, said spray tube extending laterally from the first mentioned tube, and an abutment secured to the exterior of the container and positioned in the path of the spray tube upon rotation of the cap, whereby to engage the spray tube and lock the cap against rotation to thereby maintain the valve closed, said spray tube being bendable so that it may move past the abutment upon rotation of the cap.
